CLAIM

The ornamental design for an insole, as shown and described.

DESCRIPTION

FIG. 1 is a front, top perspective view of an insole, showing our new design;

FIG. 2 is a rear, bottom perspective view thereof;

FIG. 3 is a top plan thereof;

FIG. 4 is a bottom plan view thereof;

FIG. 5 is a rear elevation view thereof;

FIG. 6 is a front elevation view thereof;

FIG. 7 is a right side elevation view thereof; and,

FIG. 8 is a left side elevation view thereof.

(Continued)

The broken lines in the figures illustrate portions of the insole that form no part of the claimed design.

1 Claim, 8 Drawing Sheets
